EXTINGUISHING AGENT FOR COMBUSTIBLE METALS

William R. Warnock, Menominee, Mich., assignor to Ansol Chemical Company, Marinette, Wis., a corporation of Wisconsin

No Drawing. Filed Sept. 28, 1955, Ser. No. 537,298

8 Claims. (Cl. 252—2)

This invention relates to a finely divided composition suitable for extinguishing fires in combustible metals and certain other substances. The invention is especially suitable for extinguishing fires in magnesium, sodium, potassium, calcium, lithium, uranium and their alloys.

The increased use of combustible metals such as sodium, potassium, magnesium, and lithium has increased the need for a non-combustible extinguishing agent for these metals which will flow through hose or pipe and can be applied in a controlled stream from a nozzle. At the present time, there are available a number of materials which will extinguish fires in combustible metals. These have the disadvantages of being combustible themselves or of being incapable of being conveyed through hose and pipe. Combustible agents are usually high flash point liquids which will not react with the burning metal under conditions of a fire. These agents extinguish by cooling the burning mass. During the extinguishing process a portion of the extinguishing agent will be ignited by the burning metal, but if the quantity of agent used is great enough the cooling action will be sufficient to extinguish the fire. If enough agent is not available a secondary flammable liquid fire will develop in the combustible extinguishing agent. Because these combustible agents can increase the intensity of a metal fire their use is limited largely to small fires.

Non-combustible agents which cannot be applied through pipe or hose are also restricted in use on combustible metal fires. These materials are applied either by shoveling or by pouring from pails. In large fires or fires where presence of moisture causes spattering of the burning metal considerable danger is involved in approaching close enough to the fire to apply the agent in either of these ways. In a confined space close enough approach for extinguishment could be difficult without special equipment for protection against the fumes produced by burning metal. The lack of a controlled stream would also make an extinguishing agent difficult to apply overhead or in small spaces under or around equipment.

These disadvantages are overcome by my present invention which provides an extinguishing composition which is non-combustible and can be applied through pipe or hose in a controlled stream for extinguishing fires in combustible metals. By proper design of the equipment my composition can be applied at a considerable distance from a fire. If the quantity of any agent used on a fire is not sufficient for complete extinguishment, the agent itself does not become involved and there is no danger of producing a fire more intense than before attempted extinguishment.

My novel composition not only flows freely from extinguishing equipment but also is highly effective in extinguishing metal fires. I employ a resin in my composition which does not inhibit free flow of the mixture at ambient temperature. I also utilize a moisture-absorbing material which has the ability to absorb consider-

2

erable moisture without change in flow properties of the mixture.

The resin used in my composition is of a type which is either plastic or thermosetting under conditions encountered in fire extinguishment. The ability to become plastic or thermosetting enables the resin to bind the mass of fire-extinguishing agent into a coherent fire-smothering blanket. It also enables the extinguishing agent to cling to and blanket vertical surfaces to control fires which would be difficult to extinguish with a non-adhering agent.

The presence of the moisture-absorbing agent improves the ability of the extinguishing agent to be discharged from a pressurized container through a hose or pipe. Also moisture which would otherwise be taken up by other ingredients of the mixture is absorbed by the absorbing agent thereby maintaining free-flow characteristics of the mixture. The advantage gained in free-flow characteristics is shown in the following Table I giving the percent dischargeable from a standard extinguishing unit using mixtures produced with and without moisture-absorbing agents.

TABLE I

	Moisture content	Average discharge	Minimum discharge	Maximum discharge
Moisture-absorbing agent present	Percent 0.0859	Percent 89.9	Percent 86.0	Percent 92.3
Moisture-absorbing agent absent	0.0853	79.7	66.2	88.5

There was little difference in actual moisture content of the mixes, but with the moisture-absorbing agent present the average discharge was better and the range between the highest and lowest values was much narrower.

In addition to a resin having characteristics previously described and an inert moisture-absorbing material, my extinguishing composition also contains an inert salt and an agent which simultaneously improves the flow of the mixture and imparts water repellency. Other flow-producing agents may also be added if found desirable.

The bulk of my composition consists of a metallic salt which is the basic extinguishing material. A salt should be chosen which will not react with the burning metal under the conditions of the fire, which can be easily made water repellent and which has suitable flow properties. Sodium chloride is the inert salt preferred for my composition. Sodium chloride can be used for controlling burning metals such as magnesium, sodium, potassium, calcium, uranium, alloys of these metals and other inflammable substances, such as phosphorous, sulfur, organic substances and the like. An inert lithium salt can be used to replace sodium chloride in special preparations for use on lithium fires. Calcium fluoride is also a suitable extinguishing agent for certain metals.

The metallic salt used should be unagglomerated under ordinary conditions and should be capable of being treated to produce water-repellency and free flow. A salt having the screen analysis shown in the following Table II is advantageous, but wider ranges are not necessarily unsatisfactory.

TABLE II

Mesh:	Percent Weight Retained
65 20	0
48	5-30
100	60-95
Pan	5-30

70 Metallic salt which is too fine does not flow properly if at all and it tends to produce an agent which will drift

away from the area to which it is being applied. Because of the large amount of surface it also requires large quantities of the agent used for imparting water-repellency. Salt that is too coarse is not satisfactory because it will not flow well and its large crystals are difficult to make water-repellent.

The moisture-absorbing material used in my fire-extinguishing composition should be capable of absorbing moisture from the salt and other ingredients without any appreciable change in physical properties. In the quantities used it should be substantially non-reacting with materials on which the extinguishing agent may be used. It should not deleteriously affect other desirable properties of the extinguishing agent such as the ability when heated to bind into a coherent mass and cling to vertical surfaces.

My preferred composition contains fuller's earth as the moisture-absorbing additive. Talc and synthetic absorptive magnesium silicate are also satisfactory for this purpose. A composition incorporating magnesium carbonate is satisfactory but has increased bulkiness decreasing the amount of extinguishing agent which can be contained in a given extinguishing unit.

The preferred particle distribution of the fuller's earth used should be such that at least 95 percent of the material will pass through a 48 mesh screen and no more than 90 percent of the material will pass through a 200 mesh screen. Finer fuller's earth satisfactorily absorbs moisture and gives desirable flow properties but inhibits the binding action produced by the resin. Coarser fuller's earth will not impart the free-flow properties desired.

The following Table III indicates the effect of particle size of fuller's earth on the discharge from a standard extinguishing unit and on the binding properties imparted by the resin.

TABLE III
Agent with five percent fuller's earth

	Grade fuller's earth		
	Preferred particle size	Fine	Coarse
On 48 mesh	3%	0	5%
On 200 mesh	70%	70%	60%
Amount discharged	85%	92%	91%
Discharge time	26 sec	24 sec	60 sec
Binding action	Satisfactory	Poor	Good

The results show that when fine fuller's earth is used the amount discharged and the time for complete discharge are satisfactory but the binding action is poor. Percentage discharge and binding action are good using coarse fuller's earth, but the rate of discharge is low and the time for complete discharge is prolonged.

The quantity of moisture-absorbent material used may vary between one percent and ten percent by weight. Greater moisture absorption will be obtained with larger quantities of material, but these larger quantities will inhibit the binding action produced by the resin.

The binding agent used is a thermoplastic or thermosetting resin capable of binding the extinguishing powder into a coherent mass under the conditions of the fire. This binding agent should be solid, non-tacky and should not coalesce or lump at ambient temperatures. It should be self-extinguishing or non-flammable when exposed to an open flame. A copolymer of vinylidene chloride and acrylonitrile having suitable properties is the resin which I prefer for a binding agent. Various phenol-formaldehyde and vinyl chloride resins give satisfactory binding action when heated but are objectionable because of the strong odors produced. The particle size of the resin used should be such that the resin particles will not interfere with the flow of extinguishing agent. The best binding action is obtained with a fine grade of resin but

coarser grades can be used if larger quantities are added to the mixture.

The quantity of resin used may vary over a considerable range. The larger the quantity the more effective the binding produced. Large quantities of resin affect other properties such as flow-ability. The preferred quantity of resin is 7 percent by weight, but the amount may vary between one percent and 20 percent by weight.

10 The water-repellency agent may consist of any suitable material such as metallic soaps of fatty acids. The agent may be applied in any suitable manner. Metallic soaps of fatty acids may be applied simply by mixing with the materials to be made water-repellent. The agent may also be applied in a solution with a volatile solvent or 15 by exposing the extinguishing composition to the vapors of the agent.

10 The agents preferred for producing water-repellency in my composition are metallic stearates including those of magnesium, zinc, calcium and other metals. These 20 stearates may be obtained in grades ranging from dense to light and fluffy. Any of these grades may be used in proper quantity. With the dense grade as much as three percent may be necessary while less than one percent of the light grade may be needed.

25 Tricalcium phosphate may be used for improving flow of the agent. Quantities up to five percent by weight of tricalcium phosphate can be used without greatly changing the properties of the mixture. Larger quantities of tricalcium phosphate will increase the bulkiness of the 30 product.

My preferred composition for an agent for extinguishing metal fires contains the indicated percentage by weight of the following ingredients:

35 86% inert salt
7% copolymer of vinylidene chloride and acrylonitrile
5% fuller's earth
1% magnesium stearate
1% tricalcium phosphate

40 These ingredients in finely divided form are mixed or ground together by any suitable means to produce a homogeneous free-flowing composition. The proportions of the materials for this composition may however vary considerably. The proportions of the components of 45 my composition may vary by weight as follows:

65-95% inert salt
1-20% copolymer of vinylidene chloride and acrylonitrile
1-10% fuller's earth

50 1-3% magnesium stearate
0-5% tricalcium phosphate

55 My composition will flow freely and can be applied on metal fires from a safe distance. It may also be applied by shoveling or pouring from a pail if so desired. Normal quantities of moisture which the composition may take up during processing or storage will be absorbed by the moisture-absorbing agent present without deterioration of the flow properties. My composition 60 can be discharged from pressurized vessels under normal conditions of operation.

I claim:

65 1. A finely divided composition for extinguishing fires in air-combustible metals consisting essentially of about 65 to about 95 weight percent metallic salt non-reactive with said burning metal, about 1 to about 10 weight percent solid inorganic moisture-adsorbing agent and about 1 to about 20 weight percent synthetic resin binder solid and non-tacky at ambient temperatures and self-extinguishing 70 when exposed to an open flame.

2. The composition as defined in claim 1, wherein the moisture-adsorbing agent is selected from the group consisting of fuller's earth, adsorptive magnesium silicate, talc and magnesium carbonate.

3. The composition as defined in claim 1, wherein the

synthetic resin binder is selected from the group consisting of vinylidene chloride-acrylonitrile copolymers, vinyl chloride polymers, and phenol formaldehyde polymers.

4. The composition of claim 1 containing also less than about 5 weight percent of tricalcium phosphate as flow-improving agent.

5. The composition of claim 1 containing also less than about 3 weight percent of a metallic salt of a higher fatty acid as water-repellent agent.

6. The composition of claim 4 containing also less than about 3 weight percent metallic salt of a higher fatty acid as water-repellent agent.

7. A finely divided composition for extinguishing fires in air-combustible metals consisting by weight of 86% sodium chloride, 7% copolymer of vinylidene chloride and acrylonitrile solid and non-tacky at ambient temperatures and self-extinguishing when exposed to an open flame, 5% fuller's earth, 1% magnesium stearate and 1% tricalcium phosphate.

8. A finely divided composition for extinguishing fires

in air-combustible metals consisting by weight of about 65 to about 95 percent sodium chloride, about 1 to about 20 percent of a copolymer of vinylidene chloride and acrylonitrile solid and non-tacky at ambient temperatures and self-extinguishing when exposed to an open flame, about 1 to about 10 percent fuller's earth, less than about 3 percent magnesium stearate, and less than about 5 percent tricalcium phosphate.
